UNITED STATES PATENT OFFICE

142,333

DESIGN FOR A SINGLE SPINDLE AUTOMATIC METALWORKING MACHINE

Alfred E. Drissner, Cleveland, Ohio, assignor to
The National Acme Company, Cleveland, Ohio,
a corporation of Ohio

Application October 6, 1944, Serial No. 115,660

Term of patent 14 years

(Cl. D54—6)

To all whom it may concern:

Be it known that I, Alfred E. Drissner, a citizen of the United States, residing at Cleveland, in the county of Cuyahoga and State of Ohio, have invented a new, original, and ornamental Design for a Single Spindle Automatic Metalworking Machine, of which the following is a specification, reference being had to the accompanying drawings, forming part thereof.

Fig. 1 is a perspective view of a single spindle

automatic metalworking machine showing my new design.

Fig. 2 is a perspective view of the rear side of the machine, with the transparent cover, shown in Fig. 1, removed.

I claim:

The ornamental design for a single spindle automatic metalworking machine, substantially as shown.

ALFRED E. DRISSNER.
